JOSEPH W. CUTHBERT, OF LOS ANGELES, CALIFORNIA, ASSIGNOR, BY MESNE ASSIGNMENTS, TO WILLIAM M. TIPPETT, OF CHICAGO, ILLINOIS

LIQUID CONTROL

Application filed October 6, 1924. Serial No. 741,979.

My invention is an improved liquid trap and vapor circulating system for refrigerators.

My invention is particularly useful in refrigeration systems in which a pump forces the refrigerant through an expansion valve into a cooling coil, the pump being of the rotary type running in oil. Since the pump is generally designed to pump vapor only, any liquid refrigerant coming into the pump causes the oil to float on top thereof, and consequently be forced into the cooling coil, leaving the pump without a lubricant, which causes it to burn out, and necessitates a replacement of parts at a loss of time and expense.

The object of my invention is to provide a trap for the liquid refrigerant, in which it is held and passed off as a vapor into the pump, thus obviating the danger of burning out the pump.

In the annexed drawing the preferred form of my invention is illustrated, but it may also be embodied in other forms, and in this application I desire to cover my invention in whatever form it may be embodied.

Figure 1 is a side view of a refrigerator with my invention embodied therein.

Figure 2 is a longitudinal sectional view of the pump housing.

Figure 3 is a longitudinal sectional view of the liquid trap.

Figure 4 is a fragmentary sectional view of the trap control valve.

Figure 5 is a longitudinal sectional view of a modified form of the pump housing and trap.

Figure 6 is a transverse sectional view of the valve used in the modified form of liquid trap.

Referring more particularly to the drawing, the refrigeration system consists of a pump 1, mounted within a housing 2, and driven by a motor 3. The refrigerant is pumped by the pump 1 into the usual condenser 4, through the expansion valve 5 into the cooling coil 6, through the trap 7, and back into the pump.

Sufficient oil is placed in housing 2 to entirely submerge the pump, the oil being

drawn into the pump through a hole 8 in the bottom thereof. The pump exhausts through a pair of pipes 9—9, which rise into the space above the oil. The vaporous refrigerant passes from the pipes 9 through the pipe 10 to the condenser 4.

Any liquid refrigerant which may be forced, or formed in the coil 6 passes into the trap 7 through the pipe 11, which extends into the port 12 in the head of said trap. A valve 13 is seated at the inner end of said port, which is normally held open to the free passage of vapor by the pressure in the coil 6. A finger 14 is pivoted below the valve 13 and bears against the inner end thereof.

A float 15 is secured to a rod 16, which is secured to the finger 14. An outlet pipe 18 extends into the trap near the top thereof, and leads to the intake of the pump 1. The float 15 normally rests on the bottom of the trap 7, and the valve 13 is thus open to the free flow of the vapor or liquid. If any of the refrigerant passes through the evaporator 6 without being vaporized, it accumulates in the bottom of the trap and gradually raises the float 15 until the finger 14 bears against the valve 13, and closes it. No more liquid refrigerant (such as SO_2) can enter until the quantity within the trap has vaporized and passed into the pump, which allows the float 15 to fall and again open the valve 13. It will thus be seen that no liquid refrigerant can pass into the pump to the detriment thereof.

In the modified form of my invention shown in Figures 5 and 6, the pump 1 is similarly placed within housing 2, and the pipes 9 extend upwardly therefrom above the level of the oil in the housing.

A transverse plate 20 is positioned within the housing 2 above the pipes 9 and serves as a baffle to deflect the oil and gas downwardly thereby separating them. Spaces 21 are provided at the ends of the plate 20 through which the gas passes and thence out of the housing through the pipe 10 to the condenser.

A water jacket 22 is provided around the gland 23 through which the driveshaft 24 extends and pipes 25 and 26 extend into and out of the jacket 22. This jacket extends into

the housing 2 and into the oil within the housing so as to cool said oil in a sufficient amount to prevent vaporization thereof. A constant stream of fresh cold water flows 5 through the pipes 25 and 26 and the jacket 22.

The trap 7 consists of the usual housing into which the pipe 11 extends and out of which the pipe 17 extends to the pump 1.

A valve 27 is positioned within the trap 7 10 and the pipe 11 is threaded into one end thereof. This valve is of a well-known type in which the valve is opened by a stem 28 and is normally held closed by a spring 29, as well as by the pressure of the incoming liquid.

An arm 30 is secured to the bottom of the valve 27 and a finger 31 is pivoted thereto and bears against the end of the rod 28. A link 32 is pivoted to the bottom of the finger 31 and a second link 33 is pivoted to the arm 20 30 and to the free end of the link 32.

The float 34 is pivoted to the juncture point of the links 32 and 33. Thus it will be seen that as the float 34 rises in the trap 7, the upper end of finger 31 will be moved away from the pin 28, permitting the valve 27 to close and prevent any further passage of liquid. This causes the liquid to accumulate in the cooling coil 6, but as the pump rapidly exhausts the vapor from the trap, it produces 25 a partial vacuum therein, with the result that the refrigerant in the trap is rapidly vaporized, causing the float to fall. Valve 27 then opens, allowing part of the refrigerant to flow from the coil to the trap.

Having described my invention, I claim:

1. In a refrigerating device, an expansion valve, a cooling coil adapted to receive refrigerant from said expansion valve, a trap positioned at the opposite end of the coil and 40 at the level of the bottom thereof and connected thereto by a pipe, a valve in said pipe, means positioned in said trap for controlling said last mentioned valve, a pump connected to the upper portion of said trap, and 45 a condenser connected to said pump and to said expansion valve.

2. In a refrigerating device having a circuit comprising a compressor, a condenser, an expansion valve and an evaporator; a liquid trap positioned in said circuit between the evaporator and the compressor, a valve in 50 said trap and means for controlling the degree of opening of said valve to thereby control the flow of fluid from said evaporator 55 to said trap.

3. In a refrigerating device having a circuit comprising a compressor, a condenser, an expansion valve and an evaporator; a liquid trap positioned in said circuit between 60 the evaporator and the compressor, a valve in said trap for controlling the flow of fluid from the evaporator to the trap, a float in said trap, and a plurality of levers operatively connecting said float with said valve.

4. In a refrigerating device having a cir-

cuit comprising a compressor, a condenser, an expansion valve and an evaporator; a liquid trap positioned in said circuit between the evaporator and the compressor, a valve in 70 said trap for controlling the flow of fluid from the evaporator to the trap, a float in said trap, operatively connected with said valve, said compressor comprising a rotary gas pump adapted to be immersed in oil, an exhaust pipe leading from said pump above the level 75 of the oil and a baffle plate adjacent the upper end of said pipe.

5. In a refrigerating device, a compressor, a condenser, an expansion valve, an evaporator, means including a trap at the outlet of 80 said evaporator and connected between said evaporator and said compressor, a valve in said trap actuatable by fluid in said trap to controllably close communication between said evaporator and said trap, whereby liquid refrigerant is prevented from entering 85 said compressor from said evaporator.

In testimony whereof I affix my signature.

JOSEPH W. CUTHBERT.
